UNITED STATES PATENT OFFICE.

LOUIS A. WARREN, OF HODGENVILLE, KENTUCKY.

BUILDING BLOCK.

1,402,327

Specification of Letters Patent. Patented Jan. 3, 1922.

Application filed May 15, 1920. Serial No. 861,671.

To all whom it may concern:

Be it known that I, LOUIS A. WARREN, a citizen of the United States, residing at Hodgenville, in the county of Larue and State of Kentucky, have invented new and useful Improvements in Building Blocks, of which the following is a specification.

This invention relates to building construction, particularly to building blocks, and has for its object the provision of a building construction embodying the use of metallic plates or sheets adapted to be secured upon the frame of a building and peculiarly corrugated whereby to provide locking means for holding specially formed blocks adapted to be disposed in courses and so formed that the successive courses when engaged upon the corrugated sheet will operate to secure each preceding course.

An important object is the provision of blocks of this character which may be formed of plastic material such as cement or the like when their use is desired for exterior work or which may be formed as tiles or bricks for either exterior or interior work or which may be formed of any suitable composition or even of wood alone for interior trimming around fire places, bath rooms, or any other desired location.

Another object is the provision of blocks of this character which may be formed plain or which may be rough or ornamented in any desired manner, depending upon the character of the work.

A further object is the provision of blocks of this character which have their engaging edges interfitting whereby not only to serve as interlocks but also to serve for excluding moisture from the building.

An additional object is the provision of a building construction of the above mentioned character which will be simple and inexpensive, which may be assembled even by unskilled labor, which will be efficient and durable, and a general improvement in the art.

With the above and other objects and advantages in view, the invention consists in the details of construction to be hereinafter more fully described and claimed, and illustrated in the accompanying drawings in which—

Figure 1 is a fragmentary elevation

of a building frame showing the application of my invention. 55

Figure 2 is an elevation of a plurality of interengaged blocks,

Figure 3 is a horizontal sectional view on the line 3—3 of Figure 2, and

Figure 4 is a vertical sectional view on the line 4—4 of Figure 2.

Referring more particularly to the drawings, the letter A designates a building foundation upon which is mounted a sill B from which rise uprights C which may be either 65 of wood or metal.

In carrying out my building construction I make use of sheets or plates 10 formed of sheet metal of suitable gage and these plates are secured upon the upright C in end to 70 end relation and held in place thereon by suitable fastenings which might be screws or bolts, depending upon whether the uprights C are of wood or of metal and the sheets are provided with holes 11 for the 75 passage of such securing members. Each sheet 10 is formed with a plurality of spaced corrugations 12 which are V-shaped in cross-section and are inclined upwardly whereby to provide overhanging locking ridges. 80

After the sheets 10 are secured in position, I dispose upon them blocks 13 which may be formed of any suitable material and of any desired dimensions. The blocks are arranged in courses with their joints staggered, as 85 clearly shown and in accordance with the well known masonry construction. As shown in Fig. 1 each course is associated with one of the corrugations 12 though I prefer to associate each course with two corrugations as shown in Fig. 4. The blocks in this figure are designated by the numeral 30 90

and the corrugations by 36. Upon its rear face each block is formed with a pair of longitudinally extending V-shaped recesses 37 95 engaged upon the corrugations and each defining a retaining shoulder engaging behind the overhanging portion of the corrugation or ridge. The upper and lower edges of the blocks are inclined, as shown at 31 and the 100 inclination is downward and outward with respect to the base sheet. The purpose of this inclination is to cause a locking action between the successive courses so that the blocks will be held firmly onto the sheets or 105 plates without the employment of any addi-

tional securing means. Another advantage of this inclination is that water will be prevented from passing between the blocks when the structure is used for exterior work.

5 The meeting ends of the blocks are also inclined as shown at 32.

In order to provide additional means for holding the blocks properly assembled, the meeting ends of adjacent blocks are so 10 formed as to have interfitting engagement. This might be accomplished in various ways though I have shown the meeting edges and ends of the blocks as formed with interfitting ribs and grooves, the ribs and grooves 15 alternating as shown and the former being designated by the numeral 33 and the latter by the numeral 34.

In finishing around corners and the like, it is understood that the same general 20 design of construction may be employed in the formation of corner blocks though such are not illustrated.

From the foregoing description and a study of the drawings it will be apparent 25 that I have thus provided a simple building structure involving metallic base plates and tiles readily engageable thereon and automatically locking one another in position. It will be noted that owing to the simplicity 30 and ease of application a building may be constructed from my blocks and sheets by a

comparatively unskilled person so that a great saving in time and labor and cost of construction will be effected.

While I have shown and described the 35 preferred embodiments of my invention, it is of course to be understood that I reserve the right to make such changes in the form, construction, and arrangement of parts as will not depart from the spirit of the invention or the scope of the subjoined claim. 40

Having thus described my invention, I claim:

A wall construction comprising a metallic sheet provided with a series of longitudinally extending corrugations having sharp edges, the upper wall of each corrugation being inclined upwardly with respect to the sheet to define an overhanging flange, and a plurality of blocks disposed upon the sheet 45 and, provided on their rear faces in spaced relation to the edges with longitudinally extending grooves of the same cross sectional contour as said corrugations and defining retaining shoulders engaging behind said 50 overhanging flanges, and the edges and ends of said blocks all being beveled and formed with tongues and grooves having interfitting engagement, the upper and lower edges being inclined downwardly and outwardly. 60

In testimony whereof I affix my signature.
LOUIS A. WARREN.
